UNITED STATES PATENT OFFICE.

KIRBY S. REIST, OF SAN FRANCISCO, CALIFORNIA, ASSIGNOR TO MERGENTHALER LINOTYPE COMPANY, A CORPORATION OF NEW YORK.

TYPOGRAPHICAL MACHINE.

1,119,537.

Specification of Letters Patent.

Patented Dec. 1, 1914.

Application filed September 10, 1914. Serial No. 860,977.

To all whom it may concern:

Be it known that I, KIRBY S. REIST, a citizen of the United States, residing at San Francisco, in the county of San Francisco and State of California, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine or magazines in the order in which their characters are to appear in print and then assembled in line, the composed line transferred to the face of a mold, the mold filled with molten 15 metal to form a slug or linotype against the matrices which produce the type characters thereon, and the matrices thereafter returned through distributing mechanism to the magazines from which they started.

20 More particularly, it relates to the devices for delivering the matrices to the distributing mechanism, one of the principal features being the employment of supplemental rotary means for controlling this delivery, as will appear more fully from the following specification and as finally pointed out in the claims.

In the accompanying drawings, I have shown my invention in preferred form and 25 by way of example, and as applied to the general form of mechanism embodied in the commercial "Model 9" linotype, but obviously many changes and variations may be made therein, and in its mode of application, which will still be comprised within its spirit. Similarly, it may be adapted to other forms of typographical machines, such as typesetters, typecasters and the like, which handle type or dies, instead of 30 matrices.

Generally speaking, I desire it to be understood that I do not limit myself to any specific form or embodiment, except in so

far as such limitations are specified in the claims.

Referring to the drawings: Figure 1 is a rear view, partly in section and broken away, of a portion of the distributing mechanism, with my improvements applied thereto; Figs. 2 and 3 are similar views of the distributor box, etc., showing the parts in different positions; Fig. 4 is a section on the line 4—4 of Fig. 2; Fig. 5 is a sectional detail of the rotary controlling devices; and Fig. 6 illustrates a special form of matrix.

Referring to Fig. 1, the matrices X are delivered by the font separating mechanism A through the tube A¹ to the distributor box B, wherein they traverse the inclined guides B¹, and are then delivered singly to the regular distributing mechanism comprising the screws C. This construction in itself constitutes no part of my present invention, it being substantially the same as that embodied in the Model 9 linotype, or as presented in United States Letters Patent to J. R. Rogers, No. 848,771; and it will also be understood that my improvements are capable of a far wider application than to the specific location and mechanism thus shown by way of example.

In order to separate the matrices X and insure their individual delivery to the threads of the distributor screws C, I employ supplemental rotary controlling devices, consisting in the present instance of the disks D and E, arranged side by side or axially displaced, and offset or projecting radially in opposite directions (see Fig. 5). The precise construction and arrangement of these disks is immaterial. They may be arranged in parallel planes, or in the form of a helical screw, or in any desired way, provided that their oppositely projecting lips act alternately upon the advancing line of matrices so that the latter are detached and delivered one by one, in the manner familiar to those skilled in the art. Preferably the lips have their edges beveled or reduced to engage the individual matrices (see Fig. 5), and the matrices X are similarly

formed with beveled or reduced surfaces X¹ (see Fig. 6) to facilitate such engagement. The disks D and E are shown as mounted upon the short shaft F provided with the pinion G, which meshes into a pinion H (see Fig. 4) upon one of the screws C, thus insuring the correct timing of the disks with reference to the distributor screws.

The operation of the controlling means is as follows: In Fig. 1 the foremost matrix X is shown as resting against the first disk D. In Fig. 2 the position of the parts is that after a rotation of 180°, whereby the projecting lip of the disk D has moved out of and the lip of the disk E into operative position, thus permitting the advance of the matrix and its engagement with the disk E. In Fig. 3, the parts have returned to their original position, and the matrix has been freed and is about to pass forward into engagement with the screws C, this subsequent engaging position being also indicated by dotted lines. It will be noted that the inclined or beveled surfaces on the disks and the matrix not only facilitate and insure the correct engagement of the disks with the matrix, but also tend to feed the latter in the proper direction.

As previously stated, I have shown my invention only in preferred form and by way of illustration, and as applied in a specific location and construction. Obviously, many modifications and alterations may be made in its form and mode of adaptation, and it may be applied in numerous instances where it is desired to control the separation and delivery of type or matrices in typographical machines. These and many other changes will suggest themselves to those skilled in the art, without departure from the scope of the invention.

Having thus described my invention, its construction and mode of operation, what I claim and desire to secure by Letters Patent of the United States, is as follows:

1. In the mechanism of the class described, the combination with distributing mechanism comprising means for propelling the matrices therethrough, of supplemental rotary means acting alternately to arrest and release the passing type or matrices and effect their delivery to the distributing mechanism.

2. In a mechanism of the class described, the combination with distributing mechanism comprising means for propelling the matrices therethrough, of supplemental rotary means for controlling the delivery of type or matrices to the distributing mechanism, said rotary means comprising two radially projecting members which alternately engage the passing type or matrices.

3. In a mechanism of the class described, the combination with distributing mecha-

nism comprising means for propelling the type or matrices therethrough, of supplemental rotary means for controlling the delivery of type or matrices to the distributing mechanism, said rotary means comprising two radially projecting and axially displaced members which alternately engage the passing type or matrices.

4. In a mechanism of the class described, the combination with distributing mechanism comprising means for propelling the matrices therethrough, of supplemental rotary means for controlling the delivery of type or matrices to the distributing mechanism, said rotary means comprising two disk-shaped members which alternately engage the passing type or matrices.

5. In a mechanism of the class described, the combination with distributing mechanism comprising means for propelling the matrices therethrough, of supplemental rotary means for controlling the delivery of type or matrices to the distributing mechanism, said rotary means comprising two disk-shaped members which alternately engage the passing type or matrices, and the said members having their edges beveled or reduced to facilitate their engagement with the type or matrices.

6. In a typographical machine comprising type or matrices, the combination of distributing mechanism comprising means for propelling the type or matrices therethrough, and supplemental rotary means for controlling the delivery of the type or matrices to the distributing mechanism, the said means comprising two radially projecting members which alternately engage the passing type or matrices, the said type or matrices being beveled or reduced at their lower ends to facilitate such engagement.

7. In a typographical machine comprising type or matrices, the combination of distributing mechanism comprising means for propelling the type or matrices therethrough, and supplemental rotary means for controlling the delivery of the type or matrices to the distributing mechanism, the said devices comprising two disk-shaped members which alternately engage the type or matrices, the said members having their edges beveled or reduced and the said type or matrices having their lower ends beveled or reduced to facilitate their mutual cooperation.

8. In a mechanism of the class described, the combination with distributing mechanism comprising a rotary screw for propelling the type or matrices therethrough, of supplemental rotary means operated by the screw for controlling the delivery of the type or matrices to the distributing mechanism.

9. In a mechanism of the class described,

the combination with distributing mechanism comprising means for propelling the type or matrices therethrough, and a distributor box having an inclined guideway down which the type or matrices pass to the distributing mechanism proper, of supplemental rotary means mounted in the distributor box and acting alternately to arrest

and release the type or matrices in their passage therethrough. ¹⁰

In testimony whereof, I have affixed my signature in presence of two witnesses.

KIRBY S. REIST.
